UNITED STATES PATENT OFFICE.

AEGIDIUS J. VAN ACKEREN, OF CEDAR RAPIDS, NEBRASKA.

COMBINED HATCHING AND BROODING DEVICE.

1,212,289.

Specification of Letters Patent. Patented Jan. 16, 1917.

Application filed January 3, 1916. Serial No. 69,817.

To all whom it may concern:

Be it known that I, AEGIDIUS J. VAN ACKEREN, a citizen of the United States, residing at Cedar Rapids, in the county of Boone and State of Nebraska, have invented certain new and useful Improvements in Combined Hatching and Brooding Devices, of which the following is a specification.

This invention relates to a combined hatching and brooding device for poultry, and has for its object to provide a single structure divided into compartments each being so arranged that a suitable degree of light, ventilation, feeding conveniences, temperature and other conditions found to be favorable will be available during the period required for hatching and brooding.

The invention, among other features, has reference to the provision of a plurality of elongated sections underlaid by a metallic screen and provided with a single roof having suitable openings so that all of the sections will be accessible for purposes of cleaning and for a required control during hatching, closures being provided for the openings and arranged to prevent leakage.

Other objects to be attained will be mentioned hereinafter.

The invention consists of the novel construction, combination and arrangement of parts as described herein and claimed, and as illustrated in the accompanying drawing, wherein—

Figure 1 is a plan view of the several compartments, being a section on line 1 1 of Fig. 2. Fig. 2 is a side view of the device, one of the roof windows being shown in a raised position and broken away. Fig. 3 is a view in longitudinal section through the structure, on line 3 3 of Fig. 4. Fig. 4 is a vertical section on line 4 4 of Fig. 2, the window being shown in a closed position. Fig. 5 is a plan view showing an end portion of the structure.

Referring now to the drawing for a more particular description, I provide a plurality of elongated sections, rectangular in plan, respectively indicated at 1, 2, 3 and 4, best shown in Fig. 1, by use of the upright front wall 5, the upright, imperforate rear wall and end walls respectively indicated at 6 and 7, and the partitions 7. To exclude rodents or the like, a layer 8 of wire netting for the entire structure is provided which should rest upon the ground. Each of the elongated sections is provided with trans-

verse partitions 9 and 10, the partition 9 having a height of only a few inches and disposed at a sufficient distance from the rear wall to form a compartment for a nest 60 11. Each partition 10 is provided with a swing door 12, and the space, in each section, between a partition 9 and 10 provides a feeding compartment 13. By reason of the arrangement as described, a runway or 65 third compartment 14 is provided for each section, which is somewhat removed from the nest, the bottom of which may be covered with sand, as indicated at α in Fig. 4. The front wall 5 is provided with swing 70 doors 15 and also with removable barriers or grates 16, one of these doors and grates being provided for each section. The top of each compartment 14 is provided with a door 17 of wire netting arranged to swing 75 from the top of a partition 10. The remaining part of the structure is provided with a roof consisting, in part, of an elongated wing 18 preferably inclined at substantially 30 degrees with reference to said 80 bottom and provided at intervals of its length with openings 19, above the nests, each of said openings, preferably, being circumscribed by upset flanges 20. For each opening 19 a lid 21 is provided, and is 85 hinged upon the rod or pintle α which is supported by brackets e (Fig. 5), near the apex of the roof. Each lid 21 has a sufficient length to extend downwardly beyond the wall 6, so that rain will be conducted 90 outwardly thereof, and is provided with downwardly projecting flanges 22 adapted to be disposed outwardly of the flanges 20, when the lid is closed, to prevent rain from entering.

At 23 is indicated a second elongated wing for the roof. It is preferably disposed at a pitch, substantially of 60 degrees, and provided, above each section, with an aperture 24 (Figs. 2, 4,) circumscribed, preferably, 100 by upset flanges 25, and upon the inner side of said wing 23, for each section, is secured a sheet of wire netting 26. A plurality of frames 27 are provided, in each of which is mounted a glass plate 28. These frames are normally disposed upon flanges 25, and are adapted to swing upon the rod 29 which is disposed near the apex of the roof and which has bearings in brackets 30; and on account of the provision of flanges 25, rain will be 105 prevented from entering. This inclined portion 23 of the roof is provided, for each

section 1, 2, 3 and 4 with a ventilating aperture 37, and above each aperture is mounted a hood 38.

During the period for hatching, the doors 5 15 should remain closed. It will be noted that the compartments 11 and 13 are well housed from rain so that the setting hens will be protected as required, and that suitable provision is made for light to enter 10 from the front of the nests, the walls at the sides and rear of the nests being imperforate, all of which are favorable conditions for hatching. Also it will be seen that the runways 14 are not protected from rain, this 15 also being a desirable feature since it is well known that in instances where chicks are hatched from eggs which, during hatching, are exposed to a limited amount of moisture prove to be much stronger than those 20 hatched by use of incubators or unexposed to moisture from natural sources or derived from the ground.

Each door 12 is provided with a strand 31 (Fig. 4,) which may be under control of an 25 operator, so that the door may be opened or closed. After a brood of chickens has been hatched, the doors 12 and 15 may be opened, the grating 16 operating, as usual, to confine the hen within the section.

30 In order that water and feed may be supplied, each section is provided with a receptacle 32 for containing water, each having a drain pipe 33 extending outwardly of the 35 section, pipes 34, provided with funnels at their upper ends, being employed for conducting water to said receptacles, from the top of the roof. By this arrangement feeding may be conveniently accomplished without causing disturbance to occupants of the 40 nests, which obviously is a desirable feature, and since the pipes 34 are detached from the

receptacles 32, all surplus water may pass from said receptacles when a fresh supply enters, and water therein will not become stagnant.

45 Numerals 35 indicate feeding receptacles, and by means of the pipes 36, they may be supplied with grain or similar poultry food, as may be required.

50 As thus described, a combined hatching and brooding device is provided which may be readily transported; all of the space is arranged to advantage, and since the several sections are of like construction, it may be conveniently and economically manufactured.

55 What I claim and desire to secure by Letters Patent is,—

60 A device of the type described, including 65 chambers for hatching and brooding purposes, with a feeding compartment therebetween, the hatching compartment and feeding chamber having oppositely inclined roofs, the roof of the feeding compartment being provided with a wire-netting-covered 70 opening, said roof also having upset-flanges at the upper and lower edges of said wire-netting covered opening, a hinged frame having arranged therein a light transmitting member, said frame, with its light-transmitting member being arranged above 75 said opening and supported upon said upset-flanges, said feeding chamber roof having a ventilating aperture therein near its upper edge, guarded by a hood in continuation of the hatching-chamber roof.

75 In testimony whereof, I have affixed my signature in presence of two witnesses.

AEGIDIUS J. VAN ACKEREN.
